UNITED STATES PATENT OFFICE

128,827

DESIGN FOR A CABINET FOR AN ICE CUBING MACHINE

William Carl Pfeil, Chicago, Ill.

Application December 7, 1939, Serial No. 88,745

Term of patent 7 years

To all whom it may concern:

Be it known that I, William Carl Pfeil, a citizen of the United States, residing at Chicago, in the county of Cook and State of Illinois, have invented a new, original, and ornamental Design for a Cabinet for an Ice Cubing Machine, of which the following is a specification, reference being had to the accompanying drawing, forming a part thereof.

In the drawing:

Fig. 1 is a perspective view of a cabinet for an ice cubing machine, showing my design;

Fig. 2 is a perspective view taken from a point opposite to that of Fig. 1; and

Fig. 3 is a top plan view of the same.

The characterizing feature of the design resides in a cabinet for an ice cubing machine of the configuration shown having an upper face which slopes downwardly and rearwardly, beginning at the front, and merges into a substantially horizontal portion, there being an upstanding U-shaped frame extending crosswise to the sloping portion, and an enclosure extending therefrom toward the rear face of the cabinet and resting upon said upper face, as shown.

I claim:

The ornamental design for a cabinet for an ice cubing machine, substantially as shown and described.

WILLIAM CARL PFEIL.
